Attorney

UNITED STATES PATENT OFFICE.

OSCAR RICHTER, OF MILWAUKEE, WISCONSIN, ASSIGNOR OF ONE-HALF TO
OSCAR FRITZE, OF SAME PLACE.

GAS-BURNING ATTACHMENT FOR STOVES.

SPECIFICATION forming part of Letters Patent No. 531,749, dated January 1, 1895.

Application filed April 5, 1894. Serial No. 506,435. (No model.)

To all whom it may concern:

Be it known that I, OSCAR RICHTER, a citizen of the United States, and a resident of Milwaukee, in the county of Milwaukee, and in the State of Wisconsin, have invented certain new and useful Improvements in Gas-Burning Attachments for Stoves; and I do hereby declare that the following is a full, clear, and exact description thereof.

10 My invention has for its object to convert a cook-stove primarily constructed for burning wood or coal, into one for the utilization of gas as fuel; and it consists in certain peculiarities of construction and combination of parts hereinafter set forth with reference to the accompanying drawings and subsequently claimed.

In the drawings: Figure 1 represents a vertical longitudinal section of an ordinary wood or coal burning cook-stove and my gas-burning apparatus in connection therewith; Fig. 2, a plan view of the gas-burning apparatus; Fig. 3, a detail plan view partly in horizontal section illustrating a water-front heater; Fig. 25 4, a sectional view on line 4-4 of the first figure.

Referring by letter to the drawings A represents a portion of an ordinary wood or coal burning cook-stove having a water-front B as an attachment thereto, and in line with each top opening of the stove is a fuel-gas burner C fitted to the inner end of a horizontal pipe D, the other end of, the pipe being fitted to a bell-like mixing-chamber E that extends through the front upper door-way of said stove and is provided with a transverse centrally apertured bar b for detachable engagement with the tapered nozzle of a gas-cock F joined to a supply-pipe G parallel to the stove-front.

40 The pipes D are held together at certain intervals by transverse corrugated plates H bolted together in pairs, one above and another below said pipes, as many pairs of the clamp-plates being employed as may be found necessary or desirable.

While all of the pipes are approximately parallel for a portion of their length the inner ones having the rear burners fitted thereto necessarily diverge from each other so as to bring said burners in line with the rear open-

ings in the stove and by means of screws I working in the front and rear clamp-plates to bear on adjacent parts of the stove the structure embracing the pipes, burners and 55 said plates may be vertically adjusted to regulate the distance between the top of said stove and said burners.

The structure above specified may be readily positioned in the stove when the top-plates 60 of the same are removed, and in order that the gas-cocks may not be accidentally disengaged from the apertured cross-bars b in the mixing-chambers E, any suitable braces may be employed, those herein shown being stiff 65 metal straps J having their outer ends bent around the gas-supply-pipe G, run in against the front wall of the stove-oven and joined to similar straps K impinged against the water-front B or the front grate L if there be no 70 water-front.

As a heater for the water-front I employ a perforated pipe M arranged in front of the grate L and provided with an elbowed portion N fitted to a mixing-chamber P similar 75 to those above specified, this mixing-chamber being detachably joined to the tapered nozzle of a cock Q fitted to the gas-supply system.

A suitably bent stiff metal strap R may be run in the stove to rest upon the bottom grate 80 S under the back ledge T of said stove to serve as a brace or support for the perforated pipe or heater for the water-front.

The gas-supply fixtures may be permanent and the burner apparatus set up and taken 85 away at will with but little if any expense or trouble, this being one of the advantages of said apparatus.

While I have shown my gas-burning apparatus organized for a four-hole cook-stove the 90 same may be as readily organized for stoves or ranges having a greater or less number of holes, and the burners being adjustable said apparatus is readily adaptable to variations in stoves of different makes.

Having thus described my invention, what I claim as new, and desire to secure by Letters Patent, is—

1. An apparatus for the utilization of gas in a cook stove primarily designed for burning solid fuel, said apparatus comprising a series of horizontal pipes, transverse corrugated plates, and a mixing-chamber.

- gated clamp-plates arranged above and below the pipes and bolted together in pairs, adjusting-screws that work in certain of the plates and bear against parts of the stove, burners fitted to inner ends of the pipes to come in line with top-openings in said stove, and mixing-chambers at the outer ends of the pipes for connection with cocks of a gas-supply system.
- 10 2. An apparatus for the utilization of gas in a cook-stove primarily designed for burning solid fuel and having a water-front, said apparatus comprising a series of horizontal pipes transverse corrugated clamp-plates arranged above and below the pipes, vertically adjustable supports for the connected pipes and clamp-plates, burners fitted to the inner
- 15

ends of the pipes to come in line with top-openings of the stove, mixing chambers at the outer ends of the pipes, another burner for arrangement adjacent to the water-front of the stove, a mixing chamber in connection with the latter burner, and a gas-supply system provided with cocks connecting with the mixing chambers, substantially as set forth. ²⁵

In testimony that I claim the foregoing I have hereunto set my hand, at Milwaukee, in the county of Milwaukee and State of Wisconsin, in the presence of two witnesses.

OSCAR RICHTER.
